(57) **CLAIM**

The ornamental design for a luggage or handbag handle, as shown and described.

DESCRIPTION

FIG. 1 is a front perspective view of a design for a luggage or handbag handle;

FIG. 2 is a front view of the handle shown in FIG. 1;

FIG. 3 is a rear view of the handle shown in FIG. 1;

FIG. 4 is a left perspective view of the handle shown in FIG. 1;

FIG. 5 is a right perspective view of the handle shown in FIG. 1;

FIG. 6 is a top view of the handle shown in FIG. 1;

FIG. 7 is a bottom view of the handle shown in FIG. 1;

FIG. 8 is an alternative embodiment of the design for a luggage or handbag handle, the handle having an extended length and including the designed curvature at both ends of the handle; and,

FIG. 9 is a perspective view of the handle shown in FIG. 1, shown in the environment of a portion of luggage with connections, grommets, and rings.

The broken lines showing metal ring attachments are for the purposes of illustrating environment and forms no part of the claimed design. The heavier line weight broken lines represent stitching and are part of the claimed design.
